(57) CLAIM

The ornamental design for a weed torch, as shown and described.

DESCRIPTION

FIG. 1 is a front perspective view of a weed torch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a front perspective view showing the weed torch in a split state thereof;

FIG. 10 is a rear perspective view showing the weed torch in a split state thereof;

FIG. 11 is an enlarged detail view of area 11 in FIG. 1 thereof;

FIG. 12 is an enlarged detail view of area 12 in FIG. 1 thereof;

FIG. 13 is an enlarged detail view of area 13 in FIG. 1 thereof; and,

FIG. 14 is an enlarged detail view of area 14 in FIG. 2. The broken lines in the drawings illustrate the portions of the weed torch, which form no part of the claimed design. The dash-dot-dash broken lines encircling the enlarged views are for annotative purposes only and form no part of the claim thereof.
